UNITED STATES PATENT OFFICE.

ALBERT J. SCHUBERT AND JAMES L. BERRY, OF KANSAS CITY, MISSOURI.

FOLDING BED.

Application filed January 3, 1921. Serial No. 434,418.

To all whom it may concern:

Be it known that we, ALBERT J. SCHUBERT and JAMES L. BERRY, citizens of the United States, and residents of Kansas City, county 5 of Jackson, State of Missouri, have invented a certain new and useful Improvement in Folding Beds, of which the following is a complete specification.

This invention relates to folding beds 10 adapted for storage in a closet, if desired, during the day, and more especially to that class of beds in which springs are employed as counter-balances for aiding in the closing and cushioning the latter part of 15 the opening movement, and the objects of the invention are to provide a bed of the class mentioned which cannot be accidentally closed or opened, or in which it is possible for the head frame to topple over upon 20 the body of the bed. A further object is to generally improve this class of beds, and to produce a bed which is of economical, strong, and rigid construction, and which is of attractive appearance.

25 To these ends the invention consists in certain novel and useful features of construction and combinations of parts as hereinafter described and claimed; and in order that it may be fully understood reference is 30 to be had to the accompanying drawings, in which:—

Figure 1 is a side elevation of a bed embodying the invention.

Figure 2 is a top plan view of the bed in 35 open position, with the mattress fabric broken away to disclose underlying parts.

Figure 3 is a vertical cross section taken on the line III—III of Figure 2.

Figure 4 is a vertical section on the line 40 IV—IV of Figure 3.

Figure 5 is a detail perspective view of certain features, part of which are employed for securing the body of the bed in upright or folded position.

45 Figure 6 is a fragmentary perspective view disclosing how the body portion of the bed is locked in upright or folded position.

Figure 7 is an enlarged fragmentary view showing the connection between the foot rail 50 portion of the bed and the braces for securing the same in proper position relative to the body portion of the bed.

Figure 8 is a vertical section on the same scale as Figure 7, taken on the line VIII— 55 VIII of Figure 1.

Figure 9 is an enlarged vertical section

showing the type of caster connection for the head and foot frame.

In the said drawings, where like reference characters identify corresponding parts in 60 all of the figures, 1 indicates the side rails of the body portion of the bed, and 2 and 3 the head and foot rails thereof. 4 indicates the foot frame of the bed, the leg portions thereof being tubular as customary, 65 as shown by Figure 8, and fitting within the leg portions of said foot frame, are bars 5 terminating near their upper and lower ends in inwardly projecting studs 6, which project through openings 4^a in the legs, and said bars are fastened in place against longitudinal movement by shouldered bolts 7 extending through said legs and said bars, and nuts 8 engaging the ends of the bolts. Folding braces 9 and 10 are pivoted at their foot 70 ends upon the studs 6, reference to Figure 7 showing that at the pivotal points of connection, the bars 9 and 10 are provided with key-hole slots 10^a and that the studs are provided with lugs 6^a, which overlap said slots 80 when the braces occupy their operative positions, and thereby prevent disconnection thereof with the said studs, as shown clearly by Figure 7.

The opposite ends of the braces 9 and 10, 85 are pivotally connected to the foot and head ends respectively of brackets 11 secured to the respective side bars or rails 1, and stretched across the body and attached in the customary or any preferred manner to the 90 head and foot rails 2 and 3, of the body, is the customary wire fabric 12, as a resilient support for the mattress, (not shown). To prevent the mattress coming in contact with the head frame hereinafter referred to, when the body is swung upward to folded or closed position, a rigid frame 13 is secured to the head rail 2. The frame 13 terminates short of the ends of rail 2 so as to be capable of swinging between the legs of the head frame, when the bed is being closed or opened. To prevent the corners of the mattress from coming into contact with the leg portions of the head frame during the 95 operation of closing and opening the bed, pivoted guards 14 are mounted on the head rail 2 at opposite ends of the fixed frame 13, said pivoted guards being capable of swinging back against the leg portions of said head frame and sliding thereon during the 100 said operations, as will be readily understood by reference to the full and dotted

line positions of the parts in Figure 1, it being understood however with respect to the last-named positions, that when the body portion is in vertical or closed position as shown by dotted lines in said figure, the pivoted frames 14 will occupy a substantially horizontal position.

- The head frame 15 may be of any preferred contour with its marginal portion 10 preferably of tubing, and the leg portions of said head frame like the leg portions of the foot frame, are equipped with suitable casters 16, and said legs of the head frame are also preferably braced by a cross bar 17.
- 15 Arranged at the inner side of each leg portion of the head frame and bolted thereto or otherwise secured, are vertical inwardly-bowed brackets 18, provided near their upper and lower ends with inwardly-projecting 20 perforated ears or lugs 19 for pivotal engagement by hooks 20 formed on the rear legs of forwardly-projecting U-shaped frames 21, the front legs of said frames being preferably of wide and skeleton form and equipped 25 with tubular posts 22 mounted on casters 23. Supporting arms 24 are secured in any suitable manner to the upper ends of the wide arms of said side frames, and the upper ends of said arms are bifurcated to receive 30 and are pivoted to the side rails 1 of the body portion as at 25. A pair of retractile springs 26, are connected at 27 to the said side rails 1, and at their opposite ends to the clamp-brackets 28 employed in securing 35 the posts 22 to the front arms of the said side frames, the function of said springs being to act as counter-balances for the body portion, so that the latter may be more easily raised and lowered. It will be noted that 40 the said springs extend in planes nearly intersecting the pivotal points 25 so that when the bed is in unfolded position, the springs shall exert practically no pressure tending to move the body portion to a closed position, 45 but that shortly after the foot end of the bed is manually raised, the action of the springs is brought into play for the purpose of aiding such lifting operation.

A brace between the side frames mentioned, comprises a pair of triangular-shaped brackets 29 having alined inwardly-projecting arms 30 connected by an angle bar 31, the angle brackets being formed with down-turned hooks 32 engaging loops 33 integral 50 with the front arms of the said side frames, the connection with the said side frames being substantially the same as the connection of the said side frames with the ears or lugs 19.

- 55 60 For locking the body portion of the bed in upright or closed position as indicated by dotted lines in Figure 1, the following mechanism is provided:

34 is a bracket bolted rigidly to and upon 65 the brace bar 31, and bolted rigidly to

bracket 34 at 35, is a horizontal quadrant-shaped bracket 36 provided with a horizontal slot 37 receiving the horizontal brace arm 38 terminating at its front end in a depending leg-portion 39 equipped with a 70 caster 40, said brace arm 38 being pivoted for swinging movement in a horizontal plane, to the bracket 36 at point 41. Connecting the said bracket 36 with the said arm 38 beyond the pivotal point 41 thereof, 75 is a retractile spring 42, the same tending to either hold the brace arm 38 longitudinally of the bed as shown in Figure 2, or transversely thereof as indicated by the dotted line *a* in said last-named figure. When the 80 said brace arm stands in the said longitudinal position its acts as a brace to prevent the head frame from toppling over upon the body portion when the latter is in opened position, or is being folded or unfolded. When the said brace is swung to the transverse position mentioned, it actuates latch mechanism to lock the body portion of the bed in vertical or inoperative position, and to accomplish this, the brace 85 90 95 99 100 105 110 115 120 125 130 arm 38 is pivotally connected by a link 43, with a swinging catch 44 pivoted on cross brace 31 and provided at its free end with a tooth 45 adapted for engaging a catch arm 46 secured to the head rail 2 of the body portion of the bed. When the body portion of the bed is swung to closed position as stated, the operator by applying foot pressure on brace 38, swings the same from the position shown by full lines in Figure 2 to the dotted line position *a*, this action causing the catch 44 to swing to the position indicated in Figure 6, where it will be noted the tooth of said catch is disposed between the head rail 2 and the catch arm 46, and thus interlocked with the latter, holds the bed body portion of the bed in upright position. To unlock the said body portion of the bed preliminary to opening the same, the operator swings the brace bar 38 from the dotted position mentioned to the full line or longitudinal position shown by Figure 2, and in the last named position said brace acts to guard against any possibility of the head frame toppling over upon the body portion when the bed is in unfolded or opened position. It will also be noted that the spring 42 tends to hold the brace in its longitudinal position or in its transverse position, as in the swinging movement in either direction, the spring passes the pivotal point 41.

It will thus be seen that the mechanism described acts to secure the body portion of the bed in upright position, and also acts when the bed is in opened or unfolded position, to guard against any possibility of the head frame tilting over upon the body position.

For the purpose of locking the bed in open position, that is with the body portion hori-

- zontal, a catch 47 is pivoted to one of the side rails 1 of the body portion and is connected thereto by a retractile spring 48, the action of which is to hold the catch 47 engaged with the front end of the top of the adjacent side bracket where said top portion projects as a flange 49 over the top of the corresponding post 22, as shown most clearly in Figure 1, and said catch is connected 5 to a pull-cord 50, which extends beneath the mattress fabric 12 and through the same at its foot end, and hangs over the foot rail 3 and is equipped with a hand ring 51, so that the operator by grasping said ring and pulling upon the said pull-cord, can trip the catch 47 and thus unlock the body portion and permit the same to be swung upwardly to closed position, it being noted in this connection that the link braces 9 and 10 uniting 10 the foot frame with the body portion, assume a position which permits the foot frame to fold flatly against the normally underside of said side rails, as shown clearly by Figure 1, and that when the bed is opened 15 by pulling upon the foot frame, the latter will swing away from the body portion and at the same time through the connections described, effect the lowering of the body portion, the catch 47 automatically engaging 20 the said flange portion 49 of the said bracket so as to lock the bed in its unfolded or operative positions.

From the above description it will be apparent that we have produced a folding bed 35 embodying the features of advantage set forth as desirable in the statement of the object of the invention, and which is susceptible of modification in minor particulars without departing from the principle of 40 construction or mode of operation involved.

We claim:

1. A folding bed, comprising a head frame, a pair of parallel side frames projecting from the head frame, a body portion pivotally supported from the side 45

frames at points spaced from the head frame, retractile springs connected at one of their ends to the side frames and at their other ends to the body portion, a brace bearing a pivoted relation to and disposed between the side frames and engaging the floor at one end, and a retractile spring bearing a fixed relation at one end to the side frames and connected to the said brace at the opposite side of the pivotal point there- 50 of from the end engaging the floor.

2. A folding bed, comprising a head frame, a pair of parallel side frames projecting from the head frame, a body portion pivotally supported from the side frames at points spaced from the head frame, retractile springs connected at one of their ends to the side frames and at their other ends to the body portion, a slotted bracket supported between the side frames, a horizontally swinging brace extending through said bracket and pivoted thereto near one end and extending downward at its opposite end for engagement with the floor, and a spring for holding said brace extending longitudinally of the bed or transversely thereof. 65

3. A folding bed, comprising a head frame, a pair of parallel side frames projecting from the head frame, a body portion pivotally supported from the side frames at points spaced from the head frame, retractile springs connected at one of their ends to the side frames and at their other ends to the body portion, means connecting the side frames and acting as a brace therefor, a pivoted catch mounted on said connecting means, a catch arm secured to the body portion, a swinging brace linked to the pivoted catch, and a spring to prevent accidental movement of the brace and pivoted catch. 70

In testimony whereof we hereunto affix our signatures.

ALBERT J. SCHUBERT.

JAMES L. BERRY.
